Attorney.

UNITED STATES PATENT OFFICE.

WILLIAM WATTIE, OF WORCESTER, MASSACHUSETTS, ASSIGNOR TO THE KNOWLES LOOM WORKS, OF SAME PLACE.

LOOM.

SPECIFICATION forming part of Letters Patent No. 392,383, dated November 6, 1888.

Application filed March 9, 1888. Serial No. 266,683. (No model.)

To all whom it may concern:

Be it known that I, WILLIAM WATTIE, a citizen of the United States, residing at Worcester, in the county of Worcester and State of Massachusetts, have invented certain new and useful Improvements in Looms; and I do hereby declare that the following is a full, clear, and exact description thereof, which, in connection with the drawings, making a part of this specification, will enable others skilled in the art to which my invention belongs to make and use the same.

My invention relates to looms, and more particularly to the mechanism for operating the harness or drop-boxes in looms; and the object of my invention is to provide a safety device which will give way and break the connection between the power and the harness or box motion when either of them meets with an obstruction to their proper working, and which will at the same time automatically stop the loom without interfering with the weft or other stop motions that may be used.

Referring to the drawings, Figure 1 is a side elevation of a portion of a loom with my safety mechanism applied thereto. Fig. 2 is an elevation of some of the parts shown in Fig. 1, looking in the direction of the arrow, same figure; and Fig. 3 is a detail view, on an enlarged scale, of a detached portion of the safety device.

In the accompanying drawings, 1 represents the loom-side; 2, the arch-stand; 3, the arch; 4, the harness and box motion frame; 5, the crank-shaft end, and 6 the lay. Power is communicated to the harness and box mechanism from the crank-shaft through spur-gears 7, bevel-gears 8 and 8', clutch 12 14, shaft 9, bevel-gears 10, and cylinders 11, all in the usual manner, and as set forth in Patent No. 134,992, of January 21, 1873.

The upper part, 12, of the clutch, Figs. 1 and 3, has secured to it the downwardly-projecting clutch-pin 13, which passes loosely through the collar 14, fastened to the shaft 9. As usually constructed, the clutch-pin 13 enters a straight hole or socket in the upper side of the bevel-gear 8' a sufficient distance to hold and drive the shaft 9, the gear 8' running loosely on the shaft; but in the present construction the end of the clutch-pin 13 is bevel-

led and enters a correspondingly-beveled socket in the upper side of the gear 8', into which it is held by a spring, 15, coiled on the shaft 9 with sufficient force to drive the head 55 motion when operating in a proper manner. The force of the spring 15, adjustable by collar 16, and the angle of the bevel on the end of the clutch-pin 13, are so proportioned that when resistance to the turning of the shaft 9 60 becomes too great the end of the pin 13 slips out of its socket, thus relieving said shaft.

It sometimes happens that the harness-pattern chain 17 gets caught in turning on the chain-spool 18, which is driven by gearing 41', 65 Fig. 1, from the lower cylinder, 11, thus bringing the give-way-spring 15 into action. It also sometimes happens that the shuttle-box gets caught, preventing its being lifted by the box-motion levers 19, Fig. 2. In the loom shown 75 in the drawings the box-motion levers 19 are operated from the same cylinder-shafts 11 as the harness-motion, connection being made between the levers 19 and the box by the cord or chain 20, passing over pulleys and attached to the lifter-sleeve 21, so that when the box is stuck it also may be relieved by spring 15 letting the clutch-pin 13 slip out of its socket.

Provision is usually made for the box getting caught by placing a spring on the lifter-rod 22, Fig. 1, between the sleeve 21 and the box, on which spring the box rests, and which is strong enough to lift the box steadily, but which will give and allow the sleeve to rise without lifting the box when the latter gets 80 caught. On looms fitted with six or more cells in the shuttle-boxes it has been found exceedingly difficult to get in a spring of the length admissible that would be strong enough to lift the necessarily somewhat heavy box and 85 still be capable of being closed a distance equal to the greatest travel of the box—the requirement for perfect safety.

By my invention I do away entirely with the employment of a spring on the lifter-rod 95 22, as above described, and it will be seen that the spring 15 will act with equal effectiveness and facility, no matter about the number of cells or travel of the box.

For the purpose of picking out imperfect 100 work, mending broken warp-threads, &c., it is sometimes desirable to turn the head-motion

without turning the rest of the loom. In order to do this the clutch member 12 has been fitted to be disconnected by a lifting-fork in the groove of the clutch member pivoted near the shaft 9 and connected by a link direct to hand-lever 23. In the present instance a lever, 24, is pivoted near its center on the arm 24' on the arch-stand 2 and carries at one end a pin, which engages the groove in clutch member 12, and near the other end a cam, 25, in this instance fastened adjustably to the lever by a bolt, 26. The cam 25 is adapted to be engaged by the end 27 of the hand-lever 23 when the top part of hand-lever is thrown forward in such a manner as to lift the clutch 12 against the pressure of the spring 15. The end of the lever 24 projects beyond the cam 25 and terminates in a lug, 24", turned outward at right angles to the plane of the lever 24, and which enters a slot, 28, in the top end of link 29, which is pivoted at its lower end to the weighted end 30' of a lever, 30, pivoted to the loom-side at 31. Pivoted to the other end of the lever 30 is a link, 32, which has a slot, 32', in its upper end, which engages a pin, 33, in the locking-arm 34, pivoted to the loom-side 1 at 35.

The shipper-shaft 36 extends the length of the loom, supported in bearings on the loom-sides. On one end of said shaft 36 is the shipper-handle 37, by which said shaft is rotated, in order to operate the belt-shifting or friction-clutch-coupling devices for stopping and starting the loom, which devices, arranged in any of the common and well-known ways, are attached to the opposite end of the shipper-shaft (not shown) in such a manner that when the handle 37 is pulled forward the power is applied, and when the handle is thrown back into the position shown in Fig. 1 the power is disconnected.

The spring 38, coiled on the shipper-shaft, has one end fast in the loom-side and the other fast in the collar 39, by which the spring is tightened in coil, so as to throw the power off and the shipper 37 into position shown in Fig. 1, when the action of the spring is unobstructed. The shipper 37 is held with power on by the point 40 of the locking-arm 34 dropping by its own weight or by the action of a spring upon the pin 41, thus locking it.

When the head-driving shaft 9 meets an obstruction in the harness or box motions, the clutch-pin 13 lifts out of its socket, and through lever 24, link 29, lever 30, and link 32 lifts the catch-point 40 off the pin 41 in the shipper-handle 37, and the spring 38 on the shipper-shaft 36 throws off the power and stops the loom. In Fig. 1 these parts are shown in the position they occupy just after that operation has taken place. If there are west or other stop-motions on the loom, they are arranged to knock off and stop the loom by throwing out the catch-point 40. The end of the link 32 is slotted to allow the pin 33 to

rise with the locking-arm 34 without disturbing the clutch 12 and connections when the clutch is in gear.

In some forms of looms the brake used for effecting a quick stop is so connected that it requires a movement—generally stepping on a treadle—additional to that of throwing on a shipper to set the brake, and in such case the shipper-shaft is jointed, so that the loom can be stopped by throwing the shipper by hand without disturbing the brake-setting, and the catch 40 is only thrown out by the operation of the stop-motions, in which case it is desirable to disconnect the clutch 12 by means of the hand-lever 23 without throwing out the catch 40. In order to accomplish this the link 29 is inclined, so that when the pin 27, operated by hand-lever 23, is moved toward the cam 25, the link swings back of its own weight, letting the lug 24" on end of the lever 24 into the long part of the slot 28, so that the cam-lever may be depressed and the clutch member 12 lifted by the further action of pin 27 on cam 25 without moving the connections 31-32 and catch 40. The end 30' of lever 30 is weighted, so that when it and its connections are unconfined the link 29 will always rest with the top face of slot 28 on lug 24" of lever 24, so that the slot may always be in line to be pushed into the position shown in Fig. 1 by action of the pin 27 of hand-lever 23.

Having thus described my invention, what I claim as new, and desire to secure by Letters Patent, is—

1. In a loom, the shipper-shaft, shipper-handle fast on said shaft and provided with a pin adapted to be engaged by a locking-arm, 34, and said locking-arm 34 provided with a pin, 33, the link 32, lever 30, link 29, and lever 24, in combination with a spring-confined give-way intervening between the harness or box motions and the source of power for operating them, for the purpose stated, and the harness or box motions and means for operating the same, substantially as shown and described.

2. In a loom, the spring-confined give-way intervening between the harness or box motions and the source of power for operating them, and said harness or box motion, and means for operating the same, the lever 24, hand-lever 23, inclined link 29, provided with a slot in its upper end, lever 30, pivoted near its center to the loom-side, link 32, provided with a slot in its upper end, and the locking-arm 34, provided with a pin, 33, in combination with a shipper-handle provided with a pin, 41, adapted to be engaged by said locking-arm and fast to the shipper-shaft of the loom, and said shipper-shaft, substantially as shown and described.

WILLIAM WATTIE.
